UNITED STATES PATENT OFFICE.

GEORGE S. OTT, OF EXELAND, WISCONSIN.

AUTOMATIC SIGNAL FOR GRADE CROSSINGS.

Application filed January 5, 1925. Serial No. 577.

To all whom it may concern:

Be it known that I, GEORGE S. OTT, a citizen of the United States, residing at Exeland, in the county of Sawyer and State 5 of Wisconsin, have invented certain new and useful Improvements in an Automatic Signal for Grade Crossings, of which the following is a specification.

This invention relates to improvements 10 in visual signals for railway grade crossings and has for its primary object to provide means whereby a visual signal may be automatically actuated by the approaching of a train traveling in one direction, thus 15 giving a warning to vehicles and pedestrians of the approach of a train at the grade crossing.

One of the important objects of the present invention is to provide a rotatable visual 20 signal which is supported adjacent the grade crossing, the same being adapted to be automatically actuated by the approach of a train in one direction, the rotatable signal being clearly visible to vehicles or the like 25 which are about to approach the railroad crossing.

A further object of the invention is to provide an automatic railway signal of the above mentioned character, wherein means 30 is provided for preventing the rotation of the signal when a train is traveling in a direction opposite to one which operates the signal, the operating means for the signal being again rendered operative when a train 35 is approaching the grade crossing in a certain direction.

A still further object of the invention is to provide an automatic railway signal for grade crossings of the above mentioned 40 character, wherein means is provided for indicating that the signal operating means has been broken, said means being visible to motor vehicles or the like which are about to approach the grade crossing.

A still further object of the invention is to provide an automatic railway signal for grade crossings of the above mentioned character, which is simple in construction, inexpensive, strong and durable and furthermore adapted for the purposes for 45 which it is designated.

Other objects and advantages of this invention will become apparent during the course of the following description.

In the accompanying drawings forming

a part of this specification and in which like numerals designate like parts throughout the same:

Figure 1 is a side elevation of the device embodying my invention showing the same 60 in use.

Figure 2 is a view partly in side elevation and partly in section of the treadle and the locking and releasing means associated therewith.

Figure 3 is a sectional view taken approximately on line 3—3 of Figure 2.

Figure 4 is an enlarged fragmentary detail of the locking and releasing means associated with the treadle.

Figure 5 is a fragmentary detail side elevation with parts shown in section of the signal member, and the operating means therefor.

Figure 6 is a similar view showing the 75 position of the signal member when the operating means therefor has been broken.

Figure 7 is a detail of the signal member, and

Figure 8 is a sectional view taken approximately on line 8—8 of Figure 4.

In the drawings wherein for the purpose of illustration is shown the preferred embodiment of my invention, the numeral 1 designates a vertical supporting standard 85 which is located at a point adjacent the railway grade crossing A and alongside the rail over which the wheels of a train are adapted to pass. A bracket 2 is secured on the upper portion of the standard 1 as at 3. 90 The bracket comprises a pair of spaced plates 4 and 5 respectively. A pair of ears such as shown at 6 are formed on the lower free ends of the side plates and the purpose thereof will hereinafter be more fully described.

Secured on one side of the bracket 2, and extending outwardly therefrom is a substantially circular casing designated by the numeral 7. The same includes a pair of 100 spaced discs. The circular casing 7 is provided with a segmental cut out portion 8 and the disc of the casing adjacent the bracket 2 is provided with an arcuate slot 9, the purpose of which will also hereinafter be more fully described. The arcuate slot 105 extends from the center of the casing to the outer periphery of the casing as is clearly illustrated in Figures 5 and 6 of the drawings.

An auxiliary bracket 10 is pivotally supported at its lower end between the ears 6 of the bracket 2 on the transversely extending pivot pin 11. The auxiliary bracket 5 10 is provided with a lateral extension 12 at its upper edge, said extension being slit and adapted to rotatably support at its outer ends the shaft 13. A signaling member in the form of a fan is mounted on the outer 10 end of the shaft 13 and is indicated generally by the numeral 14. The fan includes a plurality of radially extending blades 15 and on each of which is printed or otherwise applied the word "Stop". The signaling member 14 is of such size as to be disposed within the casing 7 provided therefor and the arcuate slot 9 provides a means for receiving the shaft 13. A ratchet wheel 16 is secured on the shaft 13 and is disposed 15 between a pair of discs 17 and 18 respectively, the latter being disposed within the slit portion of the lateral extension 12 of the 20 auxiliary bracket 10.

An arm 19 extends upwardly from the 25 top of the auxiliary bracket 10 and is adapted to be disposed between the housing 20 which is arranged on the top of the bracket 2 and extends outwardly therefrom over the top of the auxiliary bracket 30 10 and the extension 12 formed thereon, and the adjacent face or disc of the circular casing 7. Pivots supported on the upper end of the arm 19 as at 21 is the plate 22, the latter having printed on each 35 of the faces thereof the word "Out of order". A sheath 23 is arranged on the top of the bracket 2 between the housing 20 and the casing 7 for normally rendering the sign plate 22 invisible as clearly illustrated in Figures 1 and 5 of the drawings.

An elongated lever 24 is disposed longitudinally within the housing 20 and the outer end thereof is provided with a pawl 25 which is adapted for cooperation with 45 the ratchet teeth of the ratchet wheel 16. The inner end of the lever is hingedly connected to the upper end of the link 26 which extends vertically through a suitable opening provided in the top of the bracket 2 in the manner clearly illustrated 50 in Figure 5. A coil spring 27 is secured at one end to the lower end of the link 26. The opposite end of the coil spring is connected to a member 28 which is carried by the auxiliary bracket 10 and extends through a suitable opening provided 55 in the outer end of the bracket 2 whereby the auxiliary bracket is supported in the position as shown in Figure 5 of the drawings.

Located at a suitable distance from the highway or grade crossing A and supported adjacent one of the rails B on the inside thereof are a pair of angular plates 60 29 and 30 respectively, the horizontal poi-

tion of the angular plate 30 being disposed on top of the outer portion of the horizontally extending portion of the angular plate 29 as is more clearly illustrated in Figure 3. A treadle designated generally by the numeral 31 is supported between the vertical spaced portions of the angular plate and is adapted for vertical slidable movement therebetween through the medium of the laterally extending pins 32 70 carried by the treadle 31 and the vertical slots 33 provided therefor in the vertical portions of the angular plates. The treadle 31 and the upper edges of the angular plates are disposed slightly below the surface of the rail B so that the flange of the wheel of the train will engage the treadle and operate the signal in a manner to be more fully described. The respective ends of the treadle as well as the ends of the vertical 75 portions of the angular plates are beveled as clearly illustrated in the drawings.

Pivots supported on the transversely extending pin 34 in the intermediate portion of the treadle 31 is the upper leg member 35. The lower end thereof is pivotally connected as at 36 to the upper end of the leg member 37. The pivot or hinge 36 is preferably of the type used in conjunction with connecting the sections of a rule or any other suitable hinge connection may be provided as is desired. The leg member 37 extends downwardly through the horizontal portion of the angular plate 29 into a suitable casing 38 supported by the bottom of the horizontal portion of the angular plate 29 as clearly illustrated in Figure 3. A curved lever 39 is pivotally supported intermediate its ends as at 40 within the casing 38, one end of the curved 100 lever 39 being provided with a socket 41 for receiving the ball shaped head 42 formed on the lower end of the leg member 37 whereby the latter is operatively connected to the lever 39. The opposite end of the 105 link 26 through the medium of the cable 43, the cable extends over a suitable guide pulley provided therefor on the upper portion of a vertical standard 44 which is arranged adjacent the treadle 31 on the 110 outside of the rail B.

A pair of vertically arranged plates 45 and 46 respectively are arranged in spaced relation within the forward portion of the treadle 31. Cooperating with the plate 45 115 is the slide locking plate 47. The locking plate and the stationary plate 45 are provided with vertical slots as is clearly illustrated in Figure 4 and the purpose of this construction will be presently apparent.

A trip member 48 is pivotally supported intermediate its ends as at 49 in the forward 120 end of the treadle 31 and the upper portion thereof extends upwardly through a suitable 125

opening 50 formed in the beveled forward end of the treadle. Connected to the lower end of the trip member 48 is the forward end of an elongated rod 51. The same extends rearwardly within the treadle 31 through the plates 45, 47 and 46. The rear portion of the rod is threaded and a pair of nuts 52 and 53 are associated therewith on opposite sides of the plate 46, the coil springs 53, 54, and 55 encircling the threaded end of the rod 51 and being disposed between the nut 52 and the plate 46, and the nut 53 and the plate 46 respectively. The purpose of the nuts is to regulate the tension of the coil springs. A shoulder 56 is formed on the forward portion of the rod 51 and is disposed adjacent the plates 45 and 47. A plate like member 57 is pivotally supported at its upper end on the pivot 49 and is disposed forwardly of the lower portion of the trip member 48 so as to be actuated thereby in the manner to be hereinafter more fully described. An elongated rod 58 is connected at its forward end to the lower end of the plate like member 57, the rod 58 extending through suitable cut out portions provided therefor in the bottom of the stationary plates 45 and 46 and being secured at its rear end to the yoke member 59, the latter in turn being secured to the pivot pin 36. A coil spring such as is shown at 60 encircles the rear portion of the elongated rod 58 and is disposed between the plate 46 and the yoke member 59. A shoulder 61 is formed on the forward portion of the elongated rod 58 and cooperates with the slidable locking plate 47 in a manner to be presently described.

Normally, the parts are arranged as shown in Figure 1 of the drawing. As a train approaches the grade crossing A traveling in the direction of the arrow, the treadle 31 will be depressed by the action of the flanges of the wheels traveling over the treadle whereupon the curved lever 39 will be actuated to exert a pull on the cable 43 and as a result actuate the lever 24 and the pawl 25 associated therewith, the latter in turn engaging the ratchet teeth of the ratchet wheel 16 causing the rotation of the shaft and the signal member 14 whereby the blade 15 will rotate and successively display each blade within the segmental cut out portion 8 of the casing 7, thus giving an indication to motor vehicles approaching the grade crossing that a train is about to cross the highway. The continual rotation of the signal member 14 will attract the attention of the drivers of motor vehicles or the like who are traveling along the highway and are about to reach the grade crossing and the rotation of the signal member will give the proper warning to the drivers of the vehicles.

To prevent the rotation of the signal

member 14 when a train is traveling in the reverse direction, the trip member 48 will be actuated by the flanges of the wheels of the train which have passed over the grade crossing. The upper portion of the trip member 48 will be moved rearwardly causing the lower portion of the trip member to engage the plate like member 57 moving the same forwardly so that a forward pull on the elongated rod 58 is exerted, moving the leg members 35 and 37 out of vertical alignment and holding the same in such position through the medium of the shoulders 61 engaging the bottom portion of the slidable plate 47. Thus when the train passes over the treadle 31, the latter will not operate the curved lever 39 due to the fact that the leg members 35 and 37 are out of vertical alignment.

The operating means is again rendered operative by a train approaching the grade crossing in the direction of the arrow, it being understood that when the flanges of the wheels of the train engage the trip 48, the upper portion thereof will be moved forwardly, causing a rearward movement of the elongated rod 51 and whereupon the beveled portion 56 will engage the upper portion of the slot formed in the sliding plate 47 moving the latter upwardly out of engagement with the shoulder 61 facilitating the return of the leg members 35 and 37 to their vertically aligning positions through the medium of the coil spring 60 whereupon the treadle may be depressed to operate the curved lever 39 and in turn actuating the pawl and ratchet mechanism through the cable 43 whereby the signal member 14 will again be caused to rotate.

Should the cable 43 accidentally break, the weight of the auxiliary bracket 10 will cause the same to swing downwardly on its pivot 11 whereupon the shaft 13 which carries the signal member 14 will move outwardly from the casing 7 through the medium of the arcuate slot 9 and further causing the plate 22 which is pivotally carried by the upper end of the arm 19 to be moved out of its sheath 23 and also swing outwardly to maintain the position shown in Figure 6, a shoulder such as is shown at 62 being formed on the pivoted end of the plate 22 being adapted for engagement with the arm 19 for limiting the downward swinging movement of the plate 22 whereby the latter will be disposed in a substantially horizontal position so that the indicia thereon may be readily visible. The position of the signal member 14 and the plate 22 when the cable 43 is broken is more clearly illustrated in Figure 6 of the drawings.

It will thus be seen from the foregoing description, that a signaling device for railway grade crossings has been provided

which is entirely automatic in its operation and will at all times be positive and efficient in its operation.

Furthermore, the simplicity of my device 5 enables the several parts comprising the same to be readily assembled or disassembled without the loss of any considerable length of time or labor.

While I have shown the preferred embodiment of my invention, it is to be understood 10 that various changes in the size, shape and arrangement of parts may be resorted to without departing from the spirit of the invention and the scope of the appended 15 claims.

Having thus described the invention, what I claim is:

1. An automatic railway signal for grade 20 crossings comprising in combination, a rotatable signal member supported adjacent the grade crossing, a treadle adapted to be depressed by a train approaching the grade crossing when traveling in one direction, means for rotating the signal when the treadle is depressed, and an auxiliary visual signal member adapted to be displayed when the operating means for actuating the rotatable signal is broken.

2. An automatic railway signal for grade 30 crossings comprising in combination, a rotatable visual signal member supported adjacent the grade crossing, a treadle adapted to be depressed by a train approaching the grade crossing when traveling in one direction, a pawl and ratchet mechanism for rotating the signal member, a cable associated with the pawl and ratchet mechanism and the treadle whereby the former is actuated by the latter, and an auxiliary visual signal 35 member adapted to be displayed automatically when the cable is broken.

3. An automatic railway signal for grade 45 crossings comprising in combination, a rotatable visual signal member supported adjacent the grade crossing, a treadle adapted to be depressed by a train approaching the grade crossing when traveling in one direction, means for rotating the signal member when the treadle is depressed, a trip mechanism 50 associated with the treadle for preventing the rotation of the signal member when a train passes over the treadle when traveling in the opposite direction.

4. An automatic railway signal for grade 55 crossings comprising in combination, a rotatable visual signal member supported adjacent the grade crossing, a treadle adapted to be depressed by a train approaching the grade crossing when traveling in one direction, means for rotating the signal member when the treadle is depressed, a trip mechanism 60 associated with the treadle for preventing the rotation of the signal member when a train passes over the treadle when traveling in the opposite direction, and

means for releasing the trip mechanism to facilitate the actuation of the signal member by a train passing over the treadle when traveling in the first mentioned direction.

5. An automatic railway signal for grade 70 crossings comprising in combination, a rotatable signal member supported adjacent the grade crossing, a treadle adapted to be depressed by a train approaching the grade crossing when traveling in one direction, means for rotating the signal when the treadle is depressed, an auxiliary visual signal member operatively associated with the rotatable signal and normally disposed in an inoperative position, said auxiliary visual signal member adapted to be displayed and moved to an operative position when the operating means for actuating the rotatable signal is broken.

6. A device of the class described comprising a supporting standard, a bracket secured on the upper portion thereof, an auxiliary bracket pivotally supported on said aforementioned bracket, a rotatable signal member carried by the auxiliary bracket, and means for actuating said signal.

7. A device of the class described comprising a supporting standard, a bracket secured on the upper portion thereof, an auxiliary bracket pivotally supported on said aforementioned bracket, a rotatable signal member carried by the auxiliary bracket, means for actuating said signal, an additional means associated with the aforementioned means for normally holding the auxiliary bracket and the rotatable signal member in an operative position.

8. A device of the class described comprising a supporting standard, a bracket secured on the upper portion thereof, an auxiliary bracket pivotally supported on said aforementioned bracket, a rotatable signal member carried by the auxiliary bracket, means for actuating said signal, an auxiliary signal member pivotally associated with the auxiliary bracket disposed in an inoperative position, said auxiliary visual signal member adapted to be automatically moved to an operative position when the operating means for the rotatable signal member becomes broken.

9. A device of the class described comprising a supporting standard, a main bracket supported on the upper portion thereof, an auxiliary bracket pivotally supported at its lower end on said main bracket, a rotatable visual signal member carried by the auxiliary bracket, pawl and ratchet mechanisms associated with the signal member for rotating the same, means for actuating their mechanisms, and means associated with the last mentioned means for holding the auxiliary bracket in an upright position.

10. A device of the class described comprising a supporting standard, a main

- bracket supported on the upper portion thereof, an auxiliary bracket pivotally supported at its lower end on said main bracket, a rotatable visual signal member carried by 5 the auxiliary bracket, pawl and ratchet mechanisms associated with the signal member for rotating the same, means for actuating their mechanisms, and means associated with the last mentioned means for 10 holding the auxiliary bracket in upright position, and an auxiliary visual signal member pivotally associated with the upper end of the auxiliary bracket, and normally disposed in an inoperative position, said auxiliary 15 visual signal member adapted to be moved to an operative position automatically when the pawl and ratchet means becomes broken.
11. An automatic railway signal for grade 20 crossings comprising in combination, a rotatable visual signal member supported adjacent the grade crossing, a treadle adapted to be depressed by a train approaching the grade crossing when traveling in one direction, means for rotating the signal member 25 when the treadle is depressed, a trip mechanism associated with the treadle for preventing the rotation of the signal member when a train passes over the treadle when traveling in the opposite direction, and resilient means for automatically releasing the trip mechanism to facilitate the actuation of the signal member by a train passing over the treadle when traveling in the first mentioned direction.
12. An automatic railway signal for grade 30 crossings comprising in combination, a rotatable visual signal member supported adjacent the grade crossing, a treadle adapted to be depressed by a train approaching the grade crossing when traveling in one direction, means for rotating the signal member 35 when the treadle is depressed, said means comprising a curved lever, an operating cable associated with the rotatable signal 40 and one end of the curved lever, a pair of leg members, the inner adjacent ends thereof being pivotally connected together, the upper end of one of said leg members being connected to the treadle, the lower end of the other leg member being operatively associated with the other end of the curved lever, means for holding said leg members in alignment with each other to permit the actuation of the curved lever and the operating means for the rotatable signal when 45 the treadle is depressed by a train approaching the grade crossing when traveling in one direction, and a trip mechanism associated with the pivotally connected leg members for preventing the actuation of the curved lever when a train passes over the treadle when traveling in the opposite direction.

In testimony whereof I affix my signature.
GEORGE S. OTT.
